US0D1074685S

(12) **United States Design Patent** (10) Patent No.: **US D1,074,685 S**
(45) Date of Patent: ** May 13, 2025

(54) **LAPTOP STAND**

(71) Applicant: **Hyper Temple AB**, Hägersten (SE)

(72) Inventors: **Erik Hjalmar Frisk**, Singapore (SG);
Robert Ragnar Gullander, Hägersten (SE)

(**) Term: **15 Years**

(21) Appl. No.: **35/520,870**

(22) Filed: **Mar. 7, 2024**

(80) **Hague Agreement Data**

Int. Filing Date: **Mar. 7, 2024**

Int. Reg. No.: **DM/236933**

Int. Reg. Date: **Mar. 7, 2024**

Int. Reg. Pub. Date: **May 17, 2024**

(51) **LOC (15) Cl.** 14-06

(52) **U.S. Cl.**

USPC **D14/447**

CLAIM

The ornamental design for a laptop stand as shown and described.

DESCRIPTION

1. Laptop stand

1.1 : Perspective

1.2 : Perspective

1.3 : Front

1.4 : Back

1.5 : Left

1.6 : Right

1.7 : Top

1.8 : Bottom

1.9 : Perspective view in folded state

1.10 : Side view in folded state

1 Claim, 10 Drawing Sheets
